UNITED STATES PATENT OFFICE

101,874

DESIGN FOR A TIE RACK

Morris H. Jeffries, Ranger, Tex.

Application September 9, 1936, Serial No. 64,784

Term of patent 14 years

To all whom it may concern:

Be it known that I, Morris H. Jeffries, a citizen of the United States, residing at Ranger, in the county of Eastland and State of Texas, have invented a new, original, and ornamental Design for a Tie Rack, of which the following is a specification, reference being had to the accompanying drawing, forming part thereof.

Figure 1 is a front elevational view of the tie rack showing my new design.

Figure 2 is a side elevational view thereof.

Figure 3 is a top plan view.

I claim:

The ornamental design for a tie rack, as shown.

MORRIS H. JEFFRIES.
